UNITED STATES PATENT OFFICE

2,359,638

FUEL FEEDER FOR FURNACES

Paul B. Greger, Glenside, Pa.

Application May 9, 1940, Serial No. 334,122

6 Claims. (Cl. 110—45)

My invention is an improved apparatus for utilizing small size coal, such as rice or barley, and for feeding and distributing such fuel and air in correct proportions for efficient combustion in any suitable type of furnace, but particularly in furnaces of the domestic heating type.

My improvements are preferably embodied in a unit comprising a pneumatic conveyor system having one end sealed by fuel drawn or fed positively into the system, at a measured rate, from a storage bin, and the other end sealed by fuel being positively ejected from the system, at a measured rate, to a grate having zones of combustion to which the blast which has conveyed the fuel is distributed proportionately to the depth of the fuel bed and the volatility of the fuel in the respective combustion zones.

The introduction and ejection of the fuel into and from the system is preferably effected by worms rotatable in tubes by a suitable motor, which also operates a blower creating a blast, of fuel-carrying intensity, through a conduit connected at one end with the blower casing and at the other end with a drum beneath the grate and containing pressure-differentiating chambers in which green fuel, from the conveyor, and partly consumed or coked fuel, from the grate, may be mixed by agitators and overfed to the lower portion of an inclined grate, over which the fuel is distributed by a rotary spreader.

The drum chambers are separated by a perforated partition depending into a fuel pool in the drum to a level below the inlet to the vertical tube leading to the grate. Agitators are rotated in both such chambers oppositely to the direction of rotation of the worm carrying fuel upwardly from the pool through the vertical tube to the grate and of the spreader which distributes the fuel over the grate.

The characteristic features and advantages of my improvements will further appear from the following description and the accompanying drawings in illustration thereof.

In the drawings, Fig. 1 is a top plan view of a fuel feeding mechanism embodying my invention, with parts broken away for clearer illustration; Fig. 2 is an irregular vertical sectional view of the mechanism taken substantially on the line 2—2 of Fig. 1; Fig. 3 is a front end view of the mechanism shown in Figs. 1 and 2, with part of the casing broken away; Fig. 4 is a fragmentary side view of the blower casing; Fig. 5 is an enlarged broken top plan view of the combustion unit of the mechanism; and Fig. 6 is a

transverse sectional view along the line 6—6 of the mechanism shown in Fig. 5.

In the embodiment of my invention illustrated in the drawings, a sheet metal housing 1 contains a covered fuel hopper 2 having vertical and inclined walls converging toward a trough 3. The trough 3 communicates through a port 4 with the end of a tube 5 containing a lateral port 6 through which it discharges to an axial extension 7 of a blower casing 8. A shaft 9 is journaled in a packed or substantially air-tight bearing 10 in the outer end of the tube 5 and has fixed thereon a worm 11. The edges of a number of blades of the worm make a loose slip fit with the inner periphery of the tube 5. The free end of the shaft 9 and worm 11 project from the tube 5 across the trough 3 and agitate granular or powdered fuel therein to facilitate suction thereof through the tube 5. The rate of feed of the fuel through the tube 5 is measured by the rate of rotation of the worm 11. The rotation of the worm may be effected at a pre-determined rate by securing a sprocket 12 to the outer end thereof and connecting such sprocket through a sprocket chain 13 with a sprocket 14 on the shaft of a speed change gear 17 within the housing 1. An electric motor 15 is connected through a flexible coupling 16 with the speed change gear 17 and has a shaft 18 journaled in the extension 1 and casing 8. The shaft 18 has fixed thereto the hub 19 of a blower rotor having vanes 20 rotatable in the casing 8 to effect the evacuation of the latter, and the parts communicating therewith, through the secantial discharge duct 21.

The duct 21 is connected through a duct 22, of any desired length, with a duct section 23 which passes through and is supported by the outer inverted conoidal shell 24 mounted on the hollow base 26. The duct section 23 discharges within an inner inverted conoidal shell 25 depending from a perforated top 27, forming a combustion grate; such top being supported by the shell 24.

The surface of the perforated top 27 inclines conoidally downward from its perimeter to the annular edge of the top of an axial tube 28 depending from the grate 27 (Fig. 6). The parts 24, 25, 26 and 28 form a hollow chambered structure herein sometimes referred to as a drum. The number and area of the apertures in the grate zone lying between the shells 24 and 25 and the number and area of apertures in the grate zone lying between the shell 25 and tube 28 are proportioned to the amount of primary

are requisite for the proper combustion of a relatively thick bed of raw coal to be burned in the inner zone and of a relatively thin bed of partially de-volatilized coal to be burned in the outer zone. The supply of air to the respective zones, to an amount requisite for effecting combustion without clinkering, is further controlled by the size and number of the apertures 25a in the shell 25 through which alone primary air of combustion is supplied to the fuel in the outer zone of the grate in the operation of the apparatus.

The bottom edge of the cylindrical shell or tube 28 lies in a plane slightly above the level of the bottom edge of the shell 25 and the bottom edges of the tube 28 and shell 25 are positioned above the bottom level of the shell 24 which rests on and makes an air-tight joint with the top of the hollow base 26.

The fuel which settles in the bottom of the receiver from the conveyor and grate forms a seal between the lower ends of the chambers 29 and 30 formed by the shells 24, 25 and 28 and prevents escape of air from the bottom of the high pressure chamber 29 to the low pressure chamber 30.

A series of agitators or plows 31 and a series of shorter agitators or plows 32 are fixed to and rotatable by the disk 33 which lies on the top of the base 26 within the shell 24 and the respective series of agitators project upwardly into the chambers 29 and 30 to mix the fuel collected therein and cause it to flow toward the center of the receiver adjacent to the bottom mouth of the tube 28.

A bevel gear 34, beneath the top of the base 26, has a hollow hub 35 projecting through an aperture in such base and fixed to the disk 33 to effect the rotation of the latter. A top-flanged bushing 36 is rotatably journaled in the hollow hub 35 and has fixed therein a vertical shaft 37 on which is fixed a helical worm 38 extending from the level of the top of the bushing 36, through the tube 28 to the top thereof; the edge of the worm making a loose slip fit with the inner periphery of the tube 28. An eccentric spreader horn 39 is fixed to the shaft 37 above the top of the worm 38 and projects radially partly over the grate 27.

The lower end of the bushing 36 projects downward through the bevel-gear 34 and has fixed theron a bevel gear 40 which meshes with a bevel gear 41 fixed to a shaft 42 journaled in bearings in the base 26. The shaft 42 also has fixed thereto a bevel gear 43 which meshes with the bevel gear 34. The bevel gears 43 and 41 lie on opposite sides of the concentric axes of the disk 33 and shaft 37 so that the rotation of the shaft 42 effects the opposite rotations of the gears 34 and 41 and therethrough of the agitator plows 31 and 32 and the worm 38 and spreader 39.

The shaft 42 may be driven thru a sprocket 43a fixed thereon and connected by a chain 44 with a sprocket 45 on the shaft of the speed change gear 17.

It will be understood that the portion of the apparatus shown in Figs. 5 and 6 will ordinarily be so placed in a furnace as to eliminate or minimize free draft past the periphery of the drum. The fuel and air supply tube will pass through an opening in the furnace wall and the supply bin and operating mechanism placed at a suitable distance from the furnace.

In the operation of the apparatus, the motor 15 rotates the worm 4, the blower vanes 20, the

worm 38, the spreader 39, and the agitators 31 and 32 at pre-determined relative rates. The rotation of the vanes 20 draws fuel and air from the hopper 2 through the tube 5 and extension 7 into the casing 8, from which they are expelled under pressure through the ducts 21, 22 and 23 into the receiver chamber 29.

When fuel blown into the chamber 29 has collected to a depth sufficient to seal the bottom edges of the tube 28 and shell 25, the rotation of the worm 38 begins to elevate fuel through the tube 28 to the level of the inner edge of the grate 27 where it is engaged by the spreader 39 and pushed over ignited readily combustible material on the grate. The continued accretion and spreading of fuel eventually provides a fuel bed of gradually decreasing depth over the entire grate area; with fresh coal of high volatile content near the center, and partially consumed coal of low volatile content near the outer edge.

A portion of the partially consumed coal and ash drops through the apertures in the grate into the chambers 29 and 30. There it is mixed with the raw coal therein and fed toward the worm 38 by the action of the plows 31 and 32 which rotate counter to the direction of rotation of the worm and maintain the fuel in the compartments 29 and 30 at approximately similar levels.

The passage of the fuel into and through the tube 5 is facilitated and regulated by the rotation of the worm 4, and if desired the degree of suction and pressure produced by the blower may be varied by the adjustment of the opening of a vent 8a in the casing 8 adjacent to the axis of the blower rotor. Ordinarily, however, such adjustment need be made only with changes in the type, size or grade of fuel used. The fuel in the bin, in the feed tubes, in the collecting receiver on the grate, control the admission and emission of air to and from the otherwise substantially enclosed system and permit desired air pressure to be built up and maintained differentially at different combustion zones of the grate. By properly proportioning, relative to one another, the admission and emission of a particular fuel and air to the system, the proper ratio thereof to one another is secured and maintained.

As the air seals formed by the fuel in the chambers 29 and 30 and in the worm passages and the limited size and number of the apertures 25a permit the maintenance of differential air pressures between the chambers 29 and 30, air at higher pressure is available to penetrate the thicker fuel bed formed above the chamber 29 than is required to penetrate the thinner fuel bed formed above the chamber 30 and the volumes of air supplied to the respective zones are approximately proportioned to the combustion requirements of the fuel in the respective zones. The number of differential pressure chambers and pressure zones of the grate may be varied in accordance with the width of the grate.

The fuel fed upward by the worm 38 follows the path of least resistance toward the surface of the fuel bed above the worm. The spreader 39 undercuts the fuel beneath the bed surface and forces the more or less compacted fuel adjacent to the grate surface outward toward the grate periphery, so that part of the fuel freshly emitted by the worm falls back into such undercut to form a depressed area in the center of the surface of the fuel bed and prevents the formation of a steep cone.

My improvements retain all the advantages of pneumatic conveyance of coal from a reservoir to

a furnace and of over-feed central supply of fuel to a grate while also providing proper proportions of primary air to the fuel and positive feeding of coal at predetermined rates into and out of the conveyor system irrespective of the moisture content of the fuel.

My apparatus permits the maintenance of any desired rate of combustion of the fuel, maintains a predetermined fire bed thickness, maintains the proper amount of air in the proper zones thus making it possible to burn a given amount of fuel at a high rate of efficiency, and precludes the possibility of reverse flow of gaseous products of combustion through the fuel supply mechanism.

Having described my invention, I claim:

1. In apparatus of the character described, the combination with an apertured grate, of a fuel collector beneath said grate, said collector containing a plurality of chambers communicating with apertures of said grate and adapted to be air-sealed from one another by fuel collected therein, means for maintaining differential air-pressures in said chambers, and mechanism for elevating fuel from said collector to said grate and distributing it in the path of air emitted from said chambers.

2. In apparatus of the character described, the combination with an apertured grate, of a housing containing a partition forming an inner chamber and an outer chamber below said grate and communicating with apertures of said grate, a conveyor for discharging fuel to said inner chamber, fuel agitators in at least one of said chambers, and mechanism for elevating the fuel from one of said chambers to said grate.

3. In apparatus of the character described, the combination with an apertured conoidal grate, of fuel collector containing chambers communicating with said apertures and having concentric conoidal walls below said grate and a tube extending downwardly from said grate, a worm rotatable in said tube, and agitators rotatable in

said collector oppositely to the direction of rotation of said worm.

4. In apparatus of the character described, the combination with an apertured conoidal grate, of 5 a means for collecting fuel below said grate and containing chambers communicating with apertures of said grate, said means having concentric conoidal walls forming an inner chamber and an outer chamber connected through restricted ports in one of said walls, a fuel supply tube extending downwardly from said grate, and means for supplying fuel and air under pressure to said means first named.

5. In apparatus of the character described, the 15 combination with a grate, of a fuel collector having a base beneath said grate, a rotor provided with agitators in said collector and having a gear beneath said base, means for discharging fuel to said collector, a worm in said collector for feeding fuel to said grate, means extending through said rotor and including a gear for rotating said worm, said worm and rotor having concentric axes, and a shaft having gears thereon on opposite sides of said axes for driving said worm and rotor in opposite directions.

6. In apparatus of the character described, the combination with an apertured conoidal grate, of a fuel collector below said grate and containing chambers communicating with apertures of 30 said grate; said collector comprising a base, an outer wall, an inner wall shorter than said outer wall, and a fuel supply tube shorter than said inner wall, said inner wall containing restricted ports, a rotor in said collector and having agitators on opposite sides of said inner wall, a gear beneath said base and connected with said rotor, a worm in said fuel supply tube, a gear beneath said base and connected with said worm, and a shaft disposed transversely of the axes of said 35 rotor and worm and having thereon gears connected with the gears aforesaid.

PAUL B. GREGER.
